BUG BAIT TRAP

Harold A. Lutes, 5128 Coralite St.,
Long Beach, Calif. 90808

Filed Aug. 4, 1975, Ser. No. 601,794

Term of patent 14 years

Int. Cl. D22—06

U.S. Cl. D22—18

FIG. 1

FIG. 4

FIG. 5

FIG. 2

FIG. 3

FIG. 6

FIG. 7

FIG. 1 is a perspective view of the bug bait trap showing my new design;

FIG. 2 is a front elevational view of the bug bait trap shown in FIG. 1;

FIG. 3 is a rear elevational view of the bug bait trap shown in FIG. 1;

FIG. 4 is a right hand end view of the bug bait trap shown in FIG. 1;

FIG. 5 is a left hand end view of the bug bait trap shown in FIG. 1;

FIG. 6 is a top view of the bug bait trap shown in FIG. 1; and

FIG. 7 is a bottom view of the bug bait trap shown in FIG. 1.

I claim:

The ornamental design for a bug bait trap, substantially as shown.
